GARMENT HANGER

Henry P. Sahlen, Burbank, Calif.

Application November 10, 1950, Serial No. 195,031

3 Claims. (Cl. 223—98)

1

The present invention relates to garment hangers and specifically to a cover which may be applied to and over the ordinary form of wire garment hanger.

It is customary with tailors, dry cleaners, valet service establishments, dress shops, and other business establishments to utilize the ordinary form of wire hanger for holding coats, suits, dresses, and the like. The wire of the wire hanger is usually of small size with the result that coats, dresses, blouses and other garments do not hang thereon in a proper manner and creases are formed in the garments. This is particularly true where steam pressing is utilized for the garment as the garment is usually hung from such a wire hanger while it is still damp. Thus, the garment becomes out of shape in addition to being creased.

An object of the present invention is to provide a cover or blank which is applied to the wire hanger so that the objectional features heretofore noted are effectively overcome.

A further object is the provision of a cover or blank for a hanger, such as the wire type, which may be easily and quickly applied to the hanger and which, when so applied, provides a suitable support for the garments and a support which holds the garment in a proper position so that unwanted creases do not result.

A further object is the provision of a cover or blank for a hanger, such as the wire type, which may be interlocked with the wire hanger to prevent shifting thereof on the hanger.

A further object is the provision of a cover or blank for a wire-type hanger which permits quantity production of the cover or blank from rigid sheet material with a minimum of waste.

A further object is the provision of a cover or blank for garment hangers wherein the blanks may be stacked and used as needed.

A further object is the provision of a cover or blank for garment hangers which is simple of construction, efficient in use, and generally superior to covers or blanks now known to the inventor.

In the drawing:

Figure 1 is a perspective view of the cover or blank shown in position on a garment hanger of the wire type; and

Figure 2 is a plan view of one of the covers or blanks of the invention and prior to a folding of the same for attachment on a garment hanger.

Referring now with particularity to the drawing and specifically to Figure 2, I have provided a blank or cover 1 which may be formed of sheet

2

material, such as a rigid cardboard. This cover or blank 1 has a front wall 2 which is scored at 3 and 4, the scoring being divergently related and provided with a pair of flaps or panels 5 and 6, the lines of scoring 3 and 4 separating the front wall 2 from said flaps. The flaps are of a length corresponding to the length of the scoring. A portion 7 is positioned intermediate the upper ends of the flaps 5 and 6, the said portion having a curved edge 8. This portion 7 forms one type of flap which is provided with a line of scoring at 9 and the portion 7 above the line of scoring 9 is provided with an aperture 10.

The front wall 2 is scored at 11 and 12 to provide end flaps 13 and 14, and the said front wall is transversely cut at 15 and 16.

The flaps 13 and 14 are substantially rectangular in form with the upper edges 17 and 18 thereof separated from the base ends 19 and 20 of the flaps 5 and 6. The flaps 5 and 6 are substantially triangular in form and said flaps have curved base ends 19 and 20, the lines of scoring 3 and 4 each forming one side which converges with respect to the outer edges or sides 21 and 22 of said flaps, with the said edges at their convergent ends curved at 23 and 24. This curved portion merges with the lines of scoring 3 and 4 and the curved edge 8 of flap 7.

In addition, the front wall is cut at 25 and 26 immediately below the lines of scoring 3 and 4 which cuts provide tabs 27 and 28.

The cover or blank 1 is adapted to be utilized in conjunction with a hanger of some type, such as the wire hanger 29 shown in Figure 1. Wire hangers are conventional and usually include a triangular member comprising a cross rod 30 and a pair of rods 31 and 32 integrally formed with the cross rod and divergently related. The said cross rod and said rods 31 and 32 are joined by curved junctions or bight portions 33 and 34. Usually the wire, at the apex portion, is twisted at 35 and terminates in a hook 36. The said twisted portion and the hook extend upwardly from the apex.

While I have shown a wire form of hanger, nevertheless it is obvious that the ordinary wooden hanger may be utilized. As stated in the objects, wire hangers are not satisfactory for the main reason that such a hanger does not properly hold a garment. It has become the practice of dry cleaners and others to provide a tube on the cross rod, the tube usually being formed of cardboard or rigid sheet material, but nothing is added to the downwardly divergent portions of the hanger. By downwardly divergent portions

I refer, of course, to the rods 31 and 32 of the hanger.

The present invention is so formed as to protect the collar of the garment whether it be a shirtwaist or coat against soiling and likewise to properly support the coat or other garment. In applying the cover or blank of the present invention, I may simultaneously pass the hook 36 and the twisted shank 35 through the aperture 10 and position the cross rod 30 between the flap portions 37, 38, and 39. Thus, one flap 38 lies on one side of the cross rod, while the flap portions 37 and 39 lie on the opposite side of said cross rod. The segment 40 is bent at right-angles along the line of scoring 9 relative to the front wall of the flap 7, it being noted that the aperture 10 is adjacent to and touches said line of scoring. Thus, the twisted shank 35 and the apex of the rods 31 and 32 lie against one surface of the flap 7. The tabs 27 and 28 are bent inwardly as shown in Figure 1 so as to lie within the curved junction or right portions 33 and 34 of the hanger. Thus lateral shifting of the wire hanger relative to the cover or blank is prevented. The rectangular flaps 13 and 14 are bent inwardly at substantially right-angles to the front wall as shown in Figure 1, whereupon the flaps 5 and 6 are bent along the lines of scoring 3 and 4 at right-angles to the front wall of the cover or blank. It will be observed that the ends 11 and 18 of the rectangular flaps 13 and 14 engage the flaps to hold the same in substantially the position shown in Figure 1.

When a garment, such as a coat, is placed upon the hanger carrying the cover or blank of the invention, the variable width of the flaps 5 and 6 which function as shoulder supports or panels will properly hold the shoulders of the garment while the flap 7 which has a neck portion will support the collar.

The cover or blank of the invention may be used by the customer as a permanent hanger. It is further obvious that the cover or blank of the present invention may be stamped from rigid sheet material and delivered to the user of such covers or blanks in stacks. It is further evident

that a cover or blank of the type of the invention is easily applied to a wire hanger within a minimum of time and expense.

I claim:

1. A garment cover for use on a wire garment hanger having downwardly divergent rods, and a cross-rod connected at the junctions of said divergent rods and provided with a hook projecting upwardly from the apex of said divergent rods, said cover comprising a sheet of rigid material having a front wall formed with a pair of shoulder supporting flaps, a pair of end flaps, and a collar supporting flap intermediate the inner ends of the shoulder supporting flaps; said shoulder supporting flaps adapted to be folded over the divergent rods and to be divergently related when so folded, and said end flaps adapted to be bent in right angular relationship to the front wall and to underlie the said shoulder supporting flaps for holding the shoulder supporting flaps in substantially right angular relationship to the front wall; the said collar supporting flap having an upwardstanding portion lying in the plane of the front wall of the cover and a portion adapted to be bent at an angle to the front wall of said cover and provided with a perforation through which the hook of the hanger is passed.

2. The combination of claim 1, and a pair of tabs in the front wall of the cover for reception within the junctions of the said wire hanger for preventing lateral shifting of the said hanger relative to the cover.

3. The combination of claim 1, the front wall of said cover formed with a pair of spaced transverse slits, providing three flaps between which the cross-rod of the wire hanger is positioned.

HENRY P. SAHLEN.
